FORM FOR SUPPORTING HOSIERY FOR CUTTING FLOAT THREADS

Harry E. Katzenmoyer, Rosedale, Pa., assignor to Fisher Hosiery Co. Inc., Reading, Pa., a corporation of Pennsylvania

Original application April 16, 1930, Serial No. 444,675. Divided and this application March 29, 1932. Serial No. 601,789

11 Claims. (Cl. 26—11)

This invention relates to an improved stocking form on which stockings may be placed for cutting off the ends of float threads which are usually left in the production of reinforced circular knit stockings.

These reinforcing threads, as a rule, are in the high spliced heel and the reinforced sole, and such extra threads are introduced during the knitting for only a portion of each circular course, and as they span the stocking tube, the portions of the float threads which extend across the interior of the stocking must be cut away as close to the fabric as possible, to neatly finish the hose.

This application is a division of my copending application Serial No. 444,675 filed April 16, 1930. The said application discloses a novel method and apparatus for not only expeditiously cutting off the loose ends of the float threads close to the fabric without damaging the latter, but which allows a number of operators stationed about a rotary table or turret, to successively place the stockings on suitable supports, to clip the floating ends of the thread, and to then remove the stockings from the forms. The present application relates to the supports or forms for holding the stockings.

An object of the invention is to provide a novel stocking form comprising spaced rods which hold a stocking taut, and yet allow the fabric to yield under the pressure of the clipper, whereby excess pressure exerted on the clipper by an operator, will be prevented from damaging the hose.

Another object is to provide a stocking support of oscillatable type, to allow the operator, after clipping the floating ends at one side of the stocking, to turn the latter to a position so that the floating ends at the opposite sides of the stocking may be clipped.

With the foregoing objects outlined and with other objects in view which will appear as the description proceeds, the invention consists in the novel features hereinafter described in detail, illustrated in the accompanying drawing, and more particularly pointed out in the appended claims.

In the drawing:

Figure 1 is a longitudinal sectional view of a stocking form or support;

Figure 2 is a transverse vertical sectional view of the form on the line 2—2 of Figure 1;

Figure 3 is a top plan view of a stocking form; and

Figure 4 is a perspective view of a form with a stocking arranged thereon, the form being shown turned to position for clipping off float

threads from one side of the stocking subsequent to removal of float threads from the opposite side.

Referring to the drawing, the numeral 12 designates a portion of a rotary carrier, table or turret which as described in my copending application carries a plurality of posts 14 which are rigidly secured thereto at their lower ends. A stocking form 16 is mounted at the upper end of each post 14 and such a form may consist of a collar 18 having a horizontal axis and provided at its inner end with an inwardly extending flange 19 which is overlapped by the edge of a circular disk 20 that is secured to the post by any suitable means, such as screws 21. This construction allows the collar 18 to turn about the disk, and for the purpose of limiting such turning to an oscillating motion, a stop pin 22, rigidly connected to the collar 18, projects through an arc-shaped slot 23, which is concentrically arranged in the stationary disk 20.

Bosses 24 which are preferably spaced 120 degrees apart on the collar, are rigidly connected to projecting rods 25 that form a triangular assembly, and have their outer ends curved and merging into one another as at 26. These merging ends form a nose for the support to receive the toe portion of a stocking which is turned inside out when it is mounted on the support; and one of the arms has a hook 27 to accommodate a special toe on certain types of stockings. This arm also has an offset or depressed portion 28 to receive the heel portion of the reversed stocking, and when the form is in the position shown in Fig. 1; it will be manifest that the offset portion 28 will function as an indicator to guide an operator in placing a stocking on the form in such a way that the ends of the float threads will project in opposite directions from the form, and will be positioned between the arms 25.

It will be understood that while the float threads during knitting of the stocking ordinarily extend approximately diametrically across the knitting cylinder from edge to edge of a reinforced area, they are intermediately severed prior to placing the stocking inside out on a form 16 for removal of the projecting end portions of the float threads. Such severing may be accomplished by an automatic attachment to the knitting machine operating during the knitting of the stocking or may subsequently be done by hand or on a separate cutting device.

The operator turns the stocking bearing form 16 until the pin 22 reaches the lower end of the slot 23 and this causes the ends of the float

threads at one side of the stocking to be positioned so that they are located on a horizontally disposed portion of the tubular stocking 31 and between opposite side bars 25 of the form. When 5 the operator moves a suitable cutting device, such as a clipper, over the horizontal portion of the stocking, the threads thereon will be clipped, and as the horizontal portion is stretched between the opposite side bars of the form, it is 10 obvious that it can yield under pressure of the clipper so that the threads may be severed close to the fabric without damaging the latter. At the same time, a suction device, provided as described in my copending application, raises the 15 ends of the float threads causing them to stand up to facilitate clipping of the same and also carries the severed ends away as soon as they are cut from the fabric.

After the clipper operator has removed the 20 float threads from one side of the stocking, the form 16 is turned to bring the ends 33 at the opposite side of the stocking uppermost as illustrated in Figure 4; in this operation the pin 22 moves to the upper end of the slot 23 again limiting the turning of the form. It will be seen that the unclipped ends 33 project upwardly from a horizontally disposed portion 34 of the stocking which is stretched between the side bars of the form which are uppermost at this time. The 25 ends 33 are clipped off in similar manner to the removal of the ends from the other side of the stocking, (which is now at the far side of the form 16 in Fig. 4) and as portion 34 is stretched between the side bars of the form the stocking 30 yields under the pressure of the clipper so that the ends 33 may be cut off close to the fabric without damaging the latter.

From the foregoing description it will be seen that I have provided a simple, rugged, and 40 readily operable form on which hosiery may be supported for the removal of float threads. It is to be particularly noted that the provision of a skeleton form permits the fabric to be yieldingly supported so that float threads may be severed close to the fabric without damage to the latter due to pressure of the clipper or other cutting tool. It is also to be noted that the oscillatable mounting provided for the form permits it to be readily turned to successively position the 45 opposite ends of float threads for cutting operations without necessity of removing and replacing the stocking. Consequently the operation of removing float threads may be simply and expeditiously performed.

55 Although a preferred embodiment of the invention has been illustrated in the drawing and described herein there are many changes and variations which may be made without departing from the invention and it is intended to include all such changes and variations within the scope of the appended claims.

What I claim is:

1. A stocking form for use in severing the loose ends of float threads from stockings, comprising a support, and rods projecting from said support and having their ends connected together, one of said rods having a hook at its outer end portion.

2. A stocking form for use in severing the 70 loose ends of float threads from stockings, comprising a support, and rods projecting from said support and having their ends connected together, one of said rods having an offset portion intermediate its ends to receive the heel of a 75 stocking when the latter is placed on the form.

3. A form for use in severing loose ends of float threads from stockings, comprising a support, and a skeleton frame of substantially triangular cross section projecting from said support for holding the surface of a stocking yieldingly supported in a plurality of angularly disposed planes, thereby enabling the removal of float threads from a stocking without damaging the fabric of the latter. 80

4. A form for use in severing the loose ends of 85 float threads from stockings, comprising a support, and a skeleton frame of substantially triangular cross section projecting from said support for holding the surface of a stocking arranged in a plurality of angularly disposed planes, and means for rotatably mounting said support to enable turning said frame for selectively presenting said planes in horizontal position. 90

5. A form for use in severing the loose ends of 95 float threads from stockings, comprising a rotatable support, a skeleton frame of substantially triangular cross section projecting from said support, and means for limiting the rotation of said support. 95

6. A device of the character described, comprising a supporting post, a stationary disk carried by said post, a collar rotatably mounted on the disk, and substantially triangularly arranged rods having their inner ends secured to the collar, and their outer ends extending toward each other. 100

7. A form for use in removing float threads 105 from stockings comprising, a support, a pair of rods secured to said support and extending in spaced relation in a plane normal to said support, and a third rod secured to said support and extending intermediate said rods out of said plane to form therewith a triangular frame for holding the surface of a stocking yieldingly supported in a plurality of intersecting planes thereby enabling removal of float threads from the stocking without 110 damaging the fabric of the latter.

8. A form for use in removing float threads 115 from stockings comprising, a support, a pair of rods secured to said support and extending in spaced relation in a plane normal to said support, and a third rod secured to said support and extending intermediate said rods out of said plane to form therewith a triangular frame for holding the surface of a stocking disposed in a plurality of intersecting planes and means for rotatably 120 mounting said support to enable turning of said frame for selectively presenting said planes in horizontal position.

9. A form for use in removing float threads 125 from stockings comprising a support, a plurality 130 of rods secured to said support and extending for the greater portion of their length in parallel relation from the vertices of an isosceles triangle described on said support to form a skeleton frame for holding the surface of a stocking yieldingly 135 supported in a plurality of angularly disposed planes thereby enabling removal of float threads from the stocking without damaging the fabric of the latter.

10. In a form for use in removing float threads 140 from stockings; a support; a stocking holding frame associated with said support comprising, a pair of rods extending for the greater portion of their length in parallel relation in a plane normal to said support and having their end portions extending transversely of said plane and joined together, and a third rod extending from said support intermediate said rods and parallel thereto to form therewith a triangular frame for holding the surface of a stocking disposed in a 145 150

plurality of intersecting planes, the end portion of said rod being offset from its axis and joined to the end portions of said pair of rods.

11. In a form for use in removing float threads from stockings; a support; a stocking holding frame comprising, a plurality of rods secured to said support and extending therefrom in substantially parallel relation for the greater portion of their length in a plurality of planes angularly

disposed relatively to said support and each including a pair of said rods thereby forming a skeleton frame having a plurality of angularly disposed sides for yieldingly supporting the surfaces of a stocking to enable removal of float threads therefrom without damaging the stocking fabric.
